OSCILLATING PISTON METER

Harry E. Kampf, Manhasset, N. Y., assignor to
Neptune Meter Company, a corporation of New
Jersey

Application December 27, 1946, Serial No. 718,669

7 Claims. (Cl. 121—68)

1

This invention relates to fluid meters of the oscillating piston type. The invention more particularly relates to an improvement in the means cooperating with the oscillating piston for preventing leakage of the fluid by the operating parts from the inlet to the outlet of the meter.

Oscillating piston meters conventionally are constructed with a casing providing a cylindrical chamber and a pair of cover plates constituting walls of the casing transverse to the axis of the cylindrical chamber. In order to provide for the typical oscillating movement of the piston in such meters, means are provided for confining a piston of cylindrical form to move so that its axis revolves about the axis of the cylindrical chamber, an edge portion of the cylindrical piston being also confined to move substantially in a rectilinear path inwardly and outwardly toward and away from the axis of the cylindrical chamber to produce the concomitant oscillating movement of the piston. In many conventional designs the means for confining the piston to revolve about the axis of the cylindrical chamber takes the form of a body concentric with the cylindrical chamber and providing a cylindrical surface with which a roller or pin carried by the piston engages. A significant feature of such oscillating piston meters also is that a partition is inserted between the inlet opening and the outlet opening of the meter which conventionally extends from the cylindrical wall of the casing toward the axis and ordinarily abuts a transverse wall between the two openings, as well as abutting the central body which provides the cylindrical guide surface, to provide fluid-tight joints with these casing walls and with the body to prevent leakage of the fluid by the partition from the inlet opening to the outlet opening.

In many conventional designs, such as that shown in the patent to C. S. Hazard, No. 1,961,688, June 5, 1934, a slot is cut in the periphery of the cylindrical piston and extends toward the axis thereof in the web of this piston to provide for cooperation of the piston with the partition wall to secure the requisite sliding movement of the piston inwardly and outwardly along the wall. The form of the slot and the provision of auxiliary devices in some designs are intended to limit so far as possible leakage past the partition wall. When the parts of such a meter are accurately made a high degree of accuracy of measurement is obtainable because of the peculiar form of the slot which provides for the oscillating movement by virtue of the combined movement of revolution about the axis of the chamber and of translation along the partition wall. To secure the desired limitation of leakage, however, skill and care are required to produce the requisite fit of the parts. Nevertheless, because of the oscillating movement of the piston, the edges of the slot at the portions thereof which are intended to engage the faces of the partition must be spaced somewhat so as to provide a certain amount of play. Because of the

2

reciprocating action of the piston within the casing this play introduces a certain amount of slap when reversal of the movement of the piston takes place transversely of the partition, bringing one or the other edge of the slot adjacent to the periphery of the piston cylinder suddenly into contact with the corresponding face of the partition.

In order to reduce the leakage in an oscillating piston meter of this type it has been proposed heretofore, as shown in the patent to Nash, No. 300,628, June 17, 1884, to provide a tongue or blade in slideable edge-to-edge contact with the partition, this tongue being pivotally connected to the piston so that as the peripheral portion of the piston moves along the partition the blade will move in a direction generally parallel to the partition inwardly and outwardly toward and away from the axis of the cylindrical casing. In this device of the prior art, however, although its purpose is to secure a leakage resisting contact of the sliding surfaces no provision has been made to prevent the slap above referred to due to the play of the piston with respect to the partition. In this device reliance is placed, as in that of the patent to Hazard, No. 1,961,688 upon the engagement of the edges of the slot at the periphery of the piston with the face of the partition to provide the guiding movement of the piston inwardly and outwardly as the axis thereof revolves about the axis of the cylindrical casing.

It is an object of the invention to provide an improved means for guiding the oscillating piston of an oscillating piston meter.

It is another object of the invention to provide guiding means for the oscillating piston which will greatly reduce or substantially eliminate the slap of the piston upon reversal of the movement thereof.

It is another object of the invention to provide for the elimination of slap concomitantly with improving the resistance to leakage of the fluid by the operating parts between the inlet and outlet openings of the meter.

It is a still further object of the invention to provide an improved guiding means for an oscillating piston meter capable of being manufactured at relatively low cost and requiring only ordinary manufacturing accuracy.

It is an additional object of the invention to provide such improved means for guiding the piston and for resisting leakage in an oscillating meter which is otherwise constructed in conventional form.

It is a feature of the invention that means are provided associated with a blade or tongue slideable in relation to the partition and in relation to the casing for preventing slap and insuring rectilinear movement of a portion of the piston adjacent the circumference thereof along the partition. The invention utilizes a blade pivotally connected to a piston and oscillatable with

respect thereto on an axis fixed in relation to the piston, the blade being arranged in edge-to-edge relation to the partition and for movement substantially in the plane thereof. This blade slidably engages in leakage resisting contact the partition as well as a wall of the cylindrical casing transverse to the axis thereof. It also engages the cylindrical wall in such leakage resisting contact. In accordance with the preferred embodiment of the invention the blade may be connected to a pivot member of cylindrical form fitting in a cylindrical recess in the piston adjacent the periphery thereof, the axis of this cylindrical recess being parallel to the axis of the cylindrical piston. Leakage of the fluid between the cylindrical pivot member substantially is prevented by properly fitting the pivot member to the recess for pivotal movement therein.

In order to provide for rectilinear movement of the pivot member and the pivotal axis thereof along the partition, guide shoes are provided connected to the pivotal member or forming a part thereof and adapted for sliding engagement with the faces of the partition. These guide shoes preferably are fixed in relation both to the blade and to the cylindrical pivot member, or all these parts may be of unitary form, so that oscillating movement of the piston on said pivotal axis may take place relative to said pivot member, said blade and said shoes. Thus, the piston may oscillate with respect to the pivot member and to the guide shoes and to the blade as these parts and the piston move together inwardly and outwardly along the partition. As the partition and the parts engaging this partition may be formed with plane surfaces and these parts may be readily fitted together with the plane surfaces in contact with each other, the cylindrical surfaces fitting in contact with each other, as above described, such sliding and oscillating movements of the piston are accomplished without slap and without detrimental leakage of the fluid by the partition and by the cylindrical pivot member and the piston. The fit of the parts in sliding and oscillating relation, however, need not be of greater accuracy than is requisite for the manufacture of the conventional meter. Moreover, the construction is such that the parts which are utilized for the improvement of the invention may be thus manufactured so as to be interchangeable and if wear occurs replacement may be easily and simply made to maintain the fit and the accuracy of the meter.

Other objects and features of the invention will appear from the description of the drawings to follow.

Fig. 1 shows a plan view of the operating parts within the casing of an oscillating meter with a portion of the piston broken away and with one cover of the casing removed;

Fig. 2 shows a section on line 2—2 of Fig. 1;

Fig. 3 shows the blade and guide shoes of the invention with relation to the partition of an oscillating meter;

Fig. 4 shows a horizontal section of an oscillating meter embodying a modification of the invention;

Fig. 5 is a section on line 5—5 of Fig. 4;

Fig. 6 shows a modified form of the blade and guide means of the invention.

In Figs. 1 and 2 is shown the assembly 1 of the operating parts of an oscillating meter having a cylindrical casing 3 and covers 5 and 7 providing walls transversely of the axis of and fastened by suitable means to the cylindrical casing

3. This fastening may be accomplished by machining or otherwise forming the covers 5 and 7 with shouldered flanges 9 and 11 to fit to the casing 3 in fluidtight contact. The cover 5 is provided in the conventional manner with a port 13 separated from a second port 15 by a portion 17 of the wall of the cover 5. The ports 13 and 15 provide the inlet and outlet openings for the fluid introduced into the chamber formed by the casing 3 and by the covers 5 and 7, which fluid in its movement from the inlet port to the outlet port impels the cylindrical piston 19 to move with its axis revolving about the axis of the cylindrical casing 3 while being guided adjacent the periphery of the piston by means, as herein-after described, to move preferably radially inwardly toward and outwardly from the axis of the cylindrical casing 3 to secure the characteristic oscillating movement of the piston to accomplish the requisite uncovering and covering of the inlet and outlet ports.

As shown in Fig. 2 a body 21 is fastened to the cover 5 by means of screws 23 tapped into the wall of the body 21. The body 21 preferably is of cylindrical form providing an exterior cylindrical surface 25 and an interior cylindrical surface 27 concentric therewith. The coincident axes of the cylindrical surfaces 25 and 27 preferably coincide also with the axis of the cylindrical casing 3. The cover 5 and the face of the body 21 adjacent thereto are finished to provide for fluid-tight contact of the body 21 with the cover 5. The annular face 29 of the body 21 opposite to the cover 5 is formed transversely of and preferably perpendicular to the common axis of the casing 3 and of the body 21 and is spaced from the inner surface 31 of the cover 7, this surface 31 preferably also being formed perpendicular to the common axis. The piston 19 is provided with a web 33 having parallel surfaces perpendicular to the axis of the piston and in leakage resisting contact with the annular surface 29 of the body 21 and the inner surface 31 of the cover 7. The piston is formed with a wall 35 surrounding a hollow space and providing concentric cylindrical surfaces 47 and 49. The annular surface 31 of piston 19 bears against the inner face of the cover 5 which is formed perpendicular to the axis of the casing 3.

Fastened in web 33 of the piston 19 concentric with the axis of this piston in a conventional manner is a stud 41 projecting axially outwardly to provide for engagement with the registering device of the meter. Fastened in the end wall of the body 21 and in the cover 5 is a pin 43 with its axis coinciding with the axis of the casing 3. This pin 43 supports a roller 45 rotatable thereon and of such diameter with respect to the diameter of the stud 41 as to be continuously in contact with the stud 41 as the piston 19 revolves about the axis of the casing 3 and of the pin 43. The diameters of the external cylindrical surface 47 and of the internal cylindrical surface 49 provided by the wall 35 of the piston 19 are such that the inner surface 49 bears upon the outer surface 25 of the body 21 as the outer surface 47 of the piston bears upon the inner surface of the cylindrical casing 3 to provide leakage resisting contact of these surfaces as the piston revolves about the axis of the casing 3. The stud 41, being in contact both with the roller 45 and the inner surface 27 of the body 21, maintains the contact of the surfaces 47 and 49 of the piston respectively with the casing 3 and the body 21 as above mentioned for all positions of the piston

19. The elements of the fluid meter having an oscillating piston thus far described are of generally conventional form.

The meter of the invention also is provided with a partition 51 which in the embodiment of Figs. 1 and 2 is fitted in a conventional manner in fluid tight engagement with a slot or recess 53 in the exterior surface of the body 21. This partition 51 also engages the portion 17 of the cover 5, being fitted fluid-tight in the slot 55 formed in this portion 17. The partition 51 at the edge thereof opposite to the recess 53 also engages a slot 57 in the casing wall 3 in fluid-tight engagement therewith. The edge 59 of the partition 51 opposite to the recess 55 is parallel to and spaced from the inner surface 31 of the cover 7 preferably a distance equal to the thickness of the web 33 of the piston between the surface 31 of the cover 7 and the annular surface 29 of the body 21 in order that the inner surface 32 of the web 33 of the piston may slidably move in leakage resisting contact with this upper edge 59 of the partition 51 as this inner surface of the web 33 slidably moves in contact with the annular surface 29 of the body 21 in the movement of the piston inwardly and outwardly with respect to the axis of the casing.

To provide against leakage of the fluid between the inlet port and the outlet port past the partition 51 while at the same time accommodating for the inward and outward movement of the piston which produces the requisite oscillation thereof, a blade 61, which may be of the same thickness as the partition 51 and of the same depth as the thickness of the web 33 of the piston, is supported for slidable movement radially with respect to the casing 3 inwardly and outwardly along the partition with one edge of the blade in contact with the edge surface 59 of the partition and the other edge of the blade in contact with the inner surface 31 of the cover 7. This blade is pivotally supported in the piston on an axis adjacent the circumferential surface 47 thereof. In the embodiment of Figs. 1 and 2 a cylindrical pivot member 63 is rotatably fitted into a cylindrical recess 65 formed in the wall 35 of the piston with the axis of the cylindrical recess parallel to the axis of the piston. The pivot member 63 is fastened to or formed as part of the blade 61 so that this blade and pivot member as a unit may pivotally move in the cylindrical recess relative to the piston 19. It will be apparent, therefore, that as the piston moves to revolve its axis about the axis of the cylindrical casing 3 the piston also may oscillate with respect to the cylindrical pivot member 63 and the blade 61 if this blade is confined to move along the length of the partition 51 and thereby to move the pivotal axis of the blade and the portion of the piston in which the axis is positioned radially inwardly and outwardly toward and away from the axis of the cylindrical casing to secure the characteristic action of the oscillating piston meter.

In order to secure the requisite radial movement of the pivotal axis or axis of oscillation of the piston along the partition 51 the pivotal member 63 is provided with guide shoes or legs 67 which extend transversely of the blade 61 and provide contact surfaces in the shoes 67 slidably engaging the faces of the partition 51. In the particular embodiment of Figs. 1 and 2 the legs 67 are shown as extensions of the cylindrical pivot member 63 providing therebetween a slot containing the axis of the pivotal member and

extending from the free ends of these legs toward and to meet the surface of the blade 61 which makes contact with the surface 59 of the partition 51. The inner end of this slot is formed as a continuation of this contact surface of the blade 61 so as to maintain the leakage resisting contact of the blade and of the pivotal member 63 with the upper surface 59 of the partition in all positions of the blade and pivotal member along the partition. In the particular embodiment of Figs. 1 and 2 also the blade 61 passes through a slot 69 formed in the casing 3 to provide leakage resisting contact of the blade 61 with this casing wall. The blade 61 is of such length as to extend into the slot 69 to afford such contact with the casing wall when the pivot member 63 is in the position at the end of its movement adjacent the cylindrical body 21. When this pivotal member is at the opposite end of its movement it will be apparent the blade will project outwardly of the casing 3. The parts shown in Figs. 1 and 2 ordinarily are contained within an exterior meter body which may be suitably designed to provide room for the projection of the blade 61.

In order to accommodate the oscillating movement of the piston 19 with respect to the cylindrical pivot member 63 and the shoes 67 extending therefrom and to avoid interfering with the full movement of the inner surface 49 of the piston 19 into contact with the exterior surface 25 of the body 21 as the piston reaches the end of its movement inwardly along the partition, the cylindrical surfaces of the pivot member 63 and of the shoes 67 are truncated as shown at 71 in Fig. 3. Similarly, these cylindrical surfaces are truncated at 72 and 73 as shown in Fig. 3 at either side of the blade 61 in order to avoid interference with the full movement of the exterior surface 47 of the piston 19 into contact with the inner surface of the cylindrical casing 3 when the piston moves outwardly along the partition 51. This truncation of the pivot member 63 and the shoes 67 in this particular embodiment is necessary because the diameter of the pivot member and of the shoes is greater than the thickness of the wall 35 of the piston. Such provision may be necessary in accommodating the device of the invention to oscillating meters of conventional construction in which the thickness of the cylinder walls 35 is not sufficient to accommodate a pivot member having a diameter large enough to provide a good bearing surface in the cylindrical recess 65 for the cylindrical member 63 and, as well, to provide substantial thickness for the legs or shoes 67 and adequate flat bearing surfaces in these shoes for contact with the faces of the partition 51.

In the embodiment of the invention illustrated in Figs. 4, 5 and 6 the construction is generally similar to that of Figs. 1 and 2, like parts carrying like reference numerals. In this embodiment, however, the piston 19 is formed with the wall 35 thereof of greater thickness than that of the embodiment of Figs. 1 and 2, this thickness in this particular embodiment being substantially equal to the diameter of the pivot member 75 of cylindrical form which is pivotally supported in a cylindrical recess 77 formed in the wall 35 of the piston 19. In the embodiment of Figs. 4, 5 and 6 the partition 51 extends from the recess 53 in the central body 21 through the wall of casing 3 without making contact with this wall. The outer end of the partition 51 is fitted 75 in a recess 79 provided in the wall of a bulge 81.

formed upon the exterior of the casing 3. The partition 51, as in the embodiment of Figs. 1 and 2, engages a recess 55 in the portion 17 of the cover 5, this cover having a portion 83 extending outwardly to cover the chamber enclosed by the wall of the bulge 81. The cover 7 also has a portion 85 which extends outwardly to cover this chamber oppositely to the portion 83 of the cover 5.

The embodiment of Figs. 4 and 5 utilizes a combined blade and guide member 81, Fig. 6, in which the blade may be formed integrally with the pivot member 75 and with guide shoes 89 extending downwardly from the blade 88 for the full length of the blade outwardly from the pivot member 75. Between the shoes 89 there is provided a slot 91 extending fully through the member 87 parallel to the blade 88 and in the plane of the axis of the pivot member 75. The inner faces of the shoes 89 are spaced apart by this slot so as to bear in contact with the faces of the partition 51 for the full extent of the length of the blade 88 to guide the guide member and the blade and the pivot member for movement in the plane of the partition 51. The length of the partition 51 and the extent of the bulge 81 outwardly from the casing 3 are such that when the piston is moved to the position in which the pivotal member 75 is adjacent the wall of the casing 3 the end of the blade 88 and the end edges of the shoes 89 project almost to but do not reach the wall of the bulge 81. The length of the blade 88 and of the shoes 89 along the partition also is such that the end edges of these members do not pass within the casing 3 when the piston moves inwardly of the casing and the pivotal member 75 is adjacent the cylindrical body 21. It will be apparent that the blade 88 and the pivotal axis of the pivot member 75 are guided for rectilinear movement along the partition 51. As this axis is positioned in the wall 35 of the piston 19 this portion of the wall 35 is given rectilinear movement inwardly and outwardly of the axis of the casing 3 between the extreme positions of the piston. The shoes 89 being of substantial extent lengthwise of the partition to insure the rectilinear movement of the axis of the pivotal member 75 also insure the correct kinematic action of the peripheral portion of the piston to secure the requisite oscillation thereof as the axis of the piston revolves about the axis of the cylindrical casing 3 without play or lost motion between the cooperating parts.

In order to accommodate for the oscillating movement of the piston relative to the guide member 87 the wall 35 of the piston is relieved slightly at both the inner cylindrical surface and the outer cylindrical surface thereof, as shown in Fig. 4 adjacent the surface of the cylindrical recess 77. It will be understood that only such relief is necessary as to prevent engagement of the edge of the piston wall with the partition 51 or with the outer surface of the shoes 89 as the piston oscillates in its movement within the casing 3.

It will be understood that the upper surface 93 of the blade 88, Figs. 5 and 6, moves in sliding leakage resisting contact with the under face of the cover 7 in the same manner as described in connection with Figs. 1 and 2, the under surface 95 of this blade similarly making contact with the upper edge surface 59 of the partition 51. The wall 3, as shown in Fig. 4, provides an opening 97 for passage therethrough of the member 87. The edges of the wall at the opening 97 are

formed to bear against the outer faces of the shoes 89 to provide leakage resisting contact therewith. It will be understood, since the shoes 89 cooperating with the partition 51 serve to guide the pivot member 75, that is, the axis thereof which is positioned in the wall 35 of the piston 19 inwardly and outwardly in the plane of the partition, that is, radially of the casing, that the wall 3 of the casing is not required to serve for guiding the blade as is the case in the embodiment of Figs. 1 and 2. The contact of the shoes 89 with the edges of the casing wall 3 serves merely to prevent leakage of the fluid into the chamber of the bulge 81 where it may pass around the edge of the partition. While in the preferred embodiment this contact may be accomplished by fitting of the surfaces of the shoes, which ordinarily would be made of metal, to the metallic wall of the casing, within the scope of the invention, if desired, other means for preventing leakage between the shoes and the casing may be adopted.

The operation of the fluid meter of the invention is generally the same as that of conventional meters. The fluid entering through one of the ports, for example the port 13, fills the chamber at the left of the piston in Fig. 1 and at the left of partition 51 and of the blade 61 cooperating therewith in the position of the piston as shown in this figure. As the outlet port 15 is uncovered by the piston the fluid in the chamber formed within the casing at the right of the piston and at the right of the partition 51 and of the blade 61 may be discharged through the opening 15. The pressure at the left of the piston is effective to move the oscillating piston, that is, the axis of the stud 41 in the counterclockwise direction about the axis of the casing and of the pin 43. Thus, in Fig. 1 the pivotal member 63 and the peripheral portion of the piston have started to move outwardly along the partition and such movement will continue until the outer circumference of the piston substantially is tangent to the inner cylindrical surface of the wall 3 of the casing adjacent the partition.

When the piston has reached this uppermost position in Fig. 1 the inlet port 13 communicates with the space within the piston and the inner surface of the wall 35 bears upon the outer surface of the body 21 to prevent passage of the fluid to the outlet port 15. The fluid pressure acting at the inside of the piston between the wall 35 thereof and the body 21 will cause the piston to pivot on the pivotal member 63 swinging toward the left in Fig. 1, the stud 41 continuing to move counterclockwise about the axis of the pin 43. This pressure continues to act as the piston is moved downwardly until the port 13 again is uncovered at the outer side of the piston. The pressure of the fluid then is brought upon the outside of the piston to continue the movement. The port 15 then becomes uncovered at the inside of the piston for discharge of the fluid within the piston through this outlet port. The fluid at the outside of the piston previously admitted through the port 13 is discharged through the port 15 as the piston continues its movement through the position shown in Fig. 1 until the piston again is in the upper tangent position.

It will be apparent from the above description that the invention provides simple means for preventing leakage past the partition, utilizing preferably devices which may be machined by ordinary methods to cylindrical and plane surfaces for securing the leakage resisting contact of such

surfaces where relative movement therebetween is necessary. The cylindrical pivot members 63 and 75 may be readily fitted to the cylindrical recesses 65 and 77. The slot 91 of the embodiment of Figs. 4, 5 and 6 between the legs or that between shoes 67 of the embodiment of Figs. 1, 2 and 3, may be machined by ordinary methods to provide the requisite close fit to the partition 51. Such ordinary methods also may be used to secure the proper fit of the surface of the blade 61 and the edge surface 59. Not only is the essential resistance to leakage thus secured but the undesirable and in many cases detrimental action which results in slap of the piston upon reversal thereof is avoided by virtue of the improved oscillating axis guiding means of the invention.

Within the scope of the invention the form and construction of this unitary element which provides the pivot, the leakage preventing blade and the guide shoes may be varied while retaining the essential features of securing rectilinear movement of the pivotal axis along the partition, that is the movement of the axis of oscillation of the piston for correct kinematic action thereof within the casing, concomitantly with providing against leakage of the fluid by the partition from the inlet of the meter to the outlet thereof. The unitary element of the invention is adapted to be made of different materials suitable to the purpose for which the meter is designed and for low cost of manufacture with accuracy consistent with the accuracy of the conventional parts of the oscillating piston meter to which the invention is applicable. All such variations and modifications of the invention are intended to be within the scope of the claims appended hereto.

The term "oscillating piston" as used in the claims designates a member supported within a casing for revolution of a central point thereof about an axis of revolution, a point adjacent the periphery of the member being confined concomitantly to move in reciprocating movement inwardly toward and outwardly away from the axis of revolution.

I claim:

1. In a fluid meter, the combination with a casing providing a chamber having a cylindrical wall and a wall transversely of said cylindrical wall, a cylindrical oscillating piston within said chamber, means for confining said piston for movement of the axis thereof about the axis of the cylindrical chamber while maintaining said axes parallel and the circumference of the piston in contact with said cylindrical wall of the casing, said casing having in said wall thereof transverse to the axis of the cylindrical chamber a fluid inlet opening and a fluid outlet opening spaced circumferentially about the axis of said cylindrical chamber, and a partition extending from said cylindrical wall of said chamber toward the axis thereof and abutting said transverse wall and cooperating with said confining means and said transverse wall to provide substantially fluid tight joints therewith, of a blade supported for movement thereof substantially in the plane of said partition inwardly and outwardly toward and away from the axis of said cylindrical chamber, said blade cooperating with said partition and with a transverse wall of said casing to provide leakage-resisting contact therewith, a pivot member rigidly connected to said blade for engaging said piston adjacent the circumference thereof for pivotal movement of said piston with respect to said blade, and means rigidly connected to said blade adjacent the pivotal axis of said

pivot member and engaging said partition for guiding said pivotal axis and said piston to move inwardly and outwardly along said partition as the axis of the cylinder of said piston is moved about the axis of said cylindrical chamber.

2. In a fluid meter, the combination with a casing providing a chamber having a cylindrical wall and a wall transversely of said cylindrical wall, a cylindrical oscillating piston within said chamber, a body within said chamber providing a cylindrical surface concentric with the axis of said cylindrical chamber, means carried by said piston and engaging said cylindrical surface of said body for confining said piston for circular movement of the axis thereof about and in parallel relation to the axis of said cylindrical chamber and with the circumference of the piston in contact with said cylindrical wall of the casing, said casing having in said wall thereof transverse to the axis of the cylindrical chamber a fluid inlet opening and a fluid outlet opening spaced circumferentially about the axis of said cylindrical chamber, and a partition extending from said cylindrical wall of said chamber toward the axis thereof and abutting said body and said transverse wall between said inlet and said outlet openings and cooperating with said body and said walls to provide substantially fluid tight joints therewith, of a pivot member pivotally engaging said piston upon a pivotal axis fixed in relation to and adjacent the circumference of said piston and parallel to the axis of the cylinder thereof, guiding shoes rigidly connected to said pivot member at either side of the pivotal axis thereof and adapted for sliding engagement with the faces of said partition to provide for movement of said pivot member and of said piston along said partition toward and away from the axis of said chamber upon movement of the axis of the cylinder of said piston about the axis of said cylindrical chamber, and a blade rigidly connected to said pivot member with the plane of the blade substantially in the plane of said partition and in edge-to-edge relation thereto for movement of said blade with said pivot member and said guiding shoes along said partition, said blade cooperating with said partition and said casing to provide leakage-resisting contacts therewith to prevent leakage of fluid by said partition from said inlet opening to said outlet opening.

3. In a fluid meter, the combination with a casing providing a chamber having a cylindrical wall and closing walls transversely of said cylindrical wall, a cylindrical oscillating piston within said chamber, a body within said chamber providing a cylindrical surface concentric with the axis of said cylindrical chamber, means carried by said piston and engaging said cylindrical surface of said body for confining said piston for circular movement of the axis thereof about and in parallel relation to the axis of said cylindrical chamber and with the circumference of the piston in contact with said cylindrical wall of the casing, said casing having in a wall thereof transverse to the axis of the cylindrical chamber a fluid inlet opening and a fluid outlet opening positioned adjacent said cylindrical wall of said casing and spaced circumferentially about the axis of said cylindrical chamber, and a partition extending from said cylindrical wall of said chamber toward the axis thereof and abutting said body and said transverse wall between said inlet and outlet openings of said wall and cooperating with said body and said cylindrical casing wall and said transverse wall to provide substantially

fluid tight joints therewith, said cylindrical oscillating piston having a web transverse to the axis of the cylinder thereof oppositely disposed in relation to said wall of said casing having said inlet and outlet openings therein, of a cylindrical pivot member engaging a cylindrical recess in said piston for pivotal movement of said piston with respect thereto upon a pivotal axis adjacent the circumference of said piston and parallel to the axis of the cylinder thereof, guiding shoes rigidly connected to said pivot member at either side of said pivotal axis thereof extending in the direction from said web toward said transverse wall of said casing in which said inlet and said outlet openings are formed and adapted for sliding engagement with the faces of said partition to provide for movement of said pivot member and of said piston along said partition toward and away from the axis of said chamber concomitantly with oscillating movement of said piston relative to said pivot member upon movement of the axis of the cylinder of said piston about the axis of said cylindrical chamber, and a blade rigidly connected to said pivot member with the plane of the blade substantially in the plane of said partition in edge-to-edge sliding relation thereto and in leakage-resisting contact therewith for movement thereof along said partition together with said pivot member and said piston, said blade also engaging in sliding relation and in leakage-resisting contact both the transverse wall of said casing opposite to that in which said openings are formed and the cylindrical wall of said casing substantially to prevent leakage of the fluid by said partition from said inlet opening to said outlet opening.

4. In a fluid meter the combination as defined in claim 3 in which said cylindrical piston is formed with a peripheral wall providing a cylindrical exterior surface for contact with said cylindrical casing wall and an internal cylindrical surface for engaging the cylindrical surface of said body, said cylindrical pivot member being of greater diameter than the thickness of said peripheral wall of said piston and being truncated to provide a surface extending generally parallel to the axis thereof to prevent substantial interference with the contact of the cylindrical wall surfaces of the piston respectively with the cylindrical wall surfaces of the casing and of the cylindrical body within the chamber provided by the casing.

5. In a fluid meter the combination as defined in claim 2 in which said guiding shoes extend from said blade in face-to-face relation with said partition at either side thereof for a substantial part of the length of said blade, the outer faces of said guiding shoes being adapted to cooperate with the cylindrical casing wall to provide leakage resisting contact therewith.

6. In a fluid meter, the combination with a casing having a peripheral wall and having inlet and outlet openings for the fluid flowing therethrough, an oscillating piston within said casing adapted to revolve about an axis of revolution concomitantly with oscillation thereof, and means including a partition between said inlet and said outlet openings extending in the direction from said peripheral wall of said casing toward said axis of revolution and cooperating with said casing to prevent leakage of fluid past said partition from said inlet opening to said outlet opening, of a unitary member providing a blade adapted to move along said partition inwardly and outwardly

with respect to said axis of revolution and to cooperate with said partition and with said casing to prevent leakage past said blade and partition of fluid from said inlet opening to said outlet opening of said casing, said unitary member providing a cylindrical portion having the axis of the cylinder thereof parallel to the plane of the blade, said cylindrical portion having a slot therein extending along said axis thereof from an end of the cylinder and formed with inner surfaces cooperating with said partition to prevent leakage past said cylindrical portion and said partition in the movement of said unitary member and said blade along said partition, the parts of said cylindrical portion of said unitary member at either side of said slot being adapted slidably to engage the faces of said partition for guiding said unitary member along said partition, said oscillating piston being formed with a peripheral wall extending about said axis of revolution of said piston and being provided with a cylindrical recess adjacent said peripheral wall having the axis thereof parallel to said axis of revolution of said piston, said recess being adapted to receive said cylindrical portion of said unitary member to provide for pivotal movement of said piston with respect to said unitary member, whereby in the revolution of said piston about said axis of revolution within the casing the axis of said recess and the peripheral portion of said piston adjacent thereto are guided to move inwardly and outwardly along said partition concomitantly with oscillation of said piston upon said axis of said recess.

35. 7. In a fluid meter, the combination as defined in claim 3 in which said cylindrical piston is formed with a peripheral wall providing a cylindrical exterior surface for contact with said cylindrical casing wall and a concentric interior 40 cylindrical surface for engaging the cylindrical surface of said body, said cylindrical pivot member providing a cylindrical bearing surface in contact with cooperating cylindrical surfaces of said recess of substantial extent which are formed in said peripheral wall of said piston at opposite sides of the pivotal axis of said pivot member to provide for the pivotal movement of said piston with respect to said pivot member, said peripheral wall having a thickness relative to the diameter of said cylindrical pivot member and the axis of 45 said pivot member being located in said peripheral wall so as to prevent contact of said cylindrical pivot member with said casing wall and with said cylindrical body surface in the movement of said piston and said blade along said partition, said peripheral wall adjacent said contacting bearing surfaces of said cylindrical pivot member and said recess being relieved to provide for said pivotal movement of said peripheral wall 50 relative to said blade.
